HEADLIGHT PROVING APPLIANCE

Luther R. Harmon, Milwaukee, Wis.

Application February 1, 1934, Serial No. 709,387

2 Claims. (Cl. 177—311)

The object of the invention is to provide a device or appliance for incorporation as a part of the equipment of motor vehicles, so that in the event of failure of the filament in a headlight, 5 the fact may be instantly indicated to the operator; to provide an appliance of this kind in which means is included to permit the operator to use the dim headlight on one side in combination with the bright and dim headlight on the other 10 in the event of failure of one bright headlight; to provide an appliance of the kind indicated in which the proving function is entirely automatic; and generally to provide a headlight proving appliance which is of simple form, susceptible of 15 cheap manufacture and of a kind that may be readily mounted in a motor vehicle without the necessity for skill on the part of the party making the installation.

With this object in view, the invention consists
20 in a construction and combination of parts of
which a preferred embodiment is illustrated in
the accompanying drawing, wherein:

The figure is a view partly in section and partly in diagram of the invention.

25 The invention comprises a switch 10 and a system of relays housed in a case 11 which is provided with binding posts 12, 14, 15 and 16 on the one side and with binding posts 17, 18, 19 and 20 on the other side. The switch 10 is of a form 30 which incorporates a pivotally mounted switch

35 which is grounded as indicated at 40. The battery 41 has one terminal 25 grounded according to the conventional practice and the other terminal is connected by means of a conductor 42 with the switch arm 21, this same terminal being also connected by means of a conductor 43 with the binding post 20. 30

35 arm 21 carried on a disk or base 22 on which are mounted the contacts 23, 24 and 25 spaced uniform angular distances apart. An additional contact 26 is also mounted on the base and spaced from the contact 25 but lies in a line passing through the pivotal mounting of the switch arm 21 and through the contact 25, so that it is engaged with the switch arm when the latter is positioned on the contact 25, as it may be in the operation of the switch. The switch may be positioned on the contacts 23, 24, respectively and in bridging relation to the contacts 25 and 26. The contacts 24 and 25 are interconnected as are the contacts 23 and 26 and the contact 23 is connected by means of a conductor 27 with the binding post 18, the contact 24 being connected by a conductor 28 with the binding post 17.

40 The relays housed in the case 11 are dual wound and their cores 44 are disposed in close proximity to a contact carrying spring leaf 45 on opposite sides of the angular supporting bracket 46 to which the leaf is secured at its 35 longitudinal center and which is fastened, in any acceptable manner, to the wall of the case. Except where it is connected with the bracket, the leaf is unattached and carries disks opposite to the relay cores, so that they may serve as armatures to flex the leaf in the event of any magnetic pull effected by the relays. Terminally the leaf is provided with contacts which engage complementary contacts carried respectively by the brackets 47 and 48, the bracket 48 being connected by a conductor 49 with the binding post 20 45 and the bracket 47 being connected by means

50 While the invention is susceptible of application where the headlights incorporate dual filaments or where dual lamps are enclosed in a single casing, or where separate bright and dim headlights are used, it is illustrated as employed in connection with headlights of the dual filament form. The dim filament 29 of the left headlight is connected by means of a conductor 30

55 of a conductor 50 with the binding post 19. The windings 51 and 52 on the two relays function alternately with their respective companion windings 53 and 54. One terminal of the winding 53 is connected by a conductor 55 with the binding post 16, a conductor 56 connecting one terminal of the winding 51 with the binding post 15. A conductor 57 connects one terminal of the wind-

with the binding post 12, the bright filament 31 being connected by means of a conductor 32 with the binding post 14. The common connection between the two filaments is grounded, as indicated at 33, this being in accordance with the conventional practice.

The bright filament 34 of the right headlight is connected by means of a conductor 35 with the binding post 15, while the dim filament 36 of said headlight is connected by means of a conductor 37 with the binding post 16, these two filaments having their common connection grounded at 33. 10

While the element for proving the filaments may be either audible, as a buzzer or bell, or visual, as a lamp or indicating instrument, it is illustrated, in the present embodiment, as visual and as consisting of the lamp 38 which may be mounted on the vehicle dash and distinctively colored to readily distinguish its illumination from that of other dash lights. One terminal of the lamp 38 is connected by means of a conductor 39 with the binding post 19, while the other terminal of the lamp is grounded as indicated at 40. The battery 41 has one terminal grounded according to the conventional practice and the other terminal is connected by means of a conductor 42 with the switch arm 21, this same terminal being also connected by means of a conductor 43 with the binding post 20. 30

The relays housed in the case 11 are dual wound and their cores 44 are disposed in close proximity to a contact carrying spring leaf 45 on opposite sides of the angular supporting bracket 46 to which the leaf is secured at its longitudinal center and which is fastened, in any acceptable manner, to the wall of the case. Except where it is connected with the bracket, the leaf is unattached and carries disks opposite to the relay cores, so that they may serve as armatures to flex the leaf in the event of any magnetic pull effected by the relays. Terminally the leaf is provided with contacts which engage complementary contacts carried respectively by the brackets 47 and 48, the bracket 48 being connected by a conductor 49 with the binding post 20 and the bracket 47 being connected by means of a conductor 50 with the binding post 19. The windings 51 and 52 on the two relays function alternately with their respective companion windings 53 and 54. One terminal of the winding 53 is connected by a conductor 55 with the binding post 16, a conductor 56 connecting one terminal of the winding 51 with the binding post 18. A conductor 57 connects one terminal of the wind- 55

ing 52 with the binding post 14, while a conductor 58 connects one terminal of the winding 54 with the binding post 12. The remaining terminals of the two windings 51 and 52 are connected in on a common conductor 59 which is electrically connected with the binding post 18. The remaining terminals of the two windings 53 and 54 are connected to a common conductor 60 which is connected to the binding post 17.

In operation, the user desiring to operate his bright headlights, will move the switch arm 21 to its first position where it engages the contact 23. Then current will flow from the positive terminal of the battery to the arm 21, contact 23, and conductor 27 to the binding post 18, thence over the conductor 59 and through the windings 51 and 52 in parallel, thence over the conductor 57, post 14, conductor 32 to the filament 31 and likewise over the conductor 56, post 15, conductor 35 to the filament 34, the two divisions of the current uniting at the ground 33 and returning to the battery. But on energizing the coils 51 and 52, the cores 44 are energized and the contact carrying leaf 45 is flexed by the attractive action, engaging its terminal contacts with the contacts carried by the brackets 41 and 43. This latter operation will establish a circuit on the proving lamp 38, current flowing from the battery 41 over the conductor 43 to the binding post 20, thence over the conductor 49 to the bracket 48, thence over the leaf 45 to the bracket 47, thence over the conductor 50 to the binding post 19 and thence over the conductor 39 to the lamp 38, returning to the battery through the ground. As long as both the filaments 31 and 34 remain intact, the fact will be indicated by the illumination of the proving light 38. Should either filament fail, however, it will open the circuit of its particular winding on the relay, so that the core of the affected relay will lose its magnetism and the adjacent section of the leaf will return to its normal position, separating its terminal contact from the bracket contact. Thus the circuit on the lamp 38 will be broken, so that the operator will be apprised of the fact that one or the other of the lamp filaments 31 or 34 has failed and he may then make the desired replacement.

If it be desired to use the dim filaments 29 and 36 instead of the bright filaments, the switch arm 20 is shifted to the position where it engages the contact 24, when current will flow from the battery to the switch arm 21, contact 24, thence over the conductor 28 to the binding post 17, thence in opposite directions over the conductor 60 to the windings 53 and 54, passing from the former over the conductor 55 to the binding post 16 and over the conductor 37 to the filament 36. The other division will pass over the conductor 58 to the binding post 12 and thence over the conductor 30 to the filament 29. The two divisions of the current will then unite at the ground 33 and return to the battery. The cores 44 will then be subject to the effect of the windings 53 and 54 and the leaf will be attracted, as before described, closing the circuit on the proving lamp 38. Should either of the dim filaments fail, its associated relay will be de-energized and the adjacent section of the leaf will return to

its normal position, opening the circuit on the proving lamp and indicating the failure of one of the dim filaments.

Should one of the bright filaments fail and it be inconvenient or impossible to make the replacement of the affected lamp, the operator may move the switch arm 21 to the position where it engages the contacts 25 and 26. Then current will flow from the battery to the switch arm and thence from the contact 26 to the contact 23 and thence over the conductor 27 to the binding post 18, flowing from this point through the undamaged bright filament as above described. Similarly, another division of the current will flow from the contact 25 to the contact 24 and thence over the conductor 28 to the binding post 17, again dividing and flowing through both of the dim filaments as above described. Thus, the relays will be energized by both the windings 53 and 54, the spring leaf being flexed to effect its terminal contact engagement to close the circuit on the proving lamp 38. The unaffected bright filament will, of course, energize its winding on its associated relay but the magnetizing force of the two windings will be cumulative, so that the leaf will be retained in contact engaging position. Thus, the arrangement for illumination of both headlights, with the advantage of the bright illumination of one where there has been a failure of the bright filament in the other, is something of great practical advantage, particularly in road driving.

The invention having been described, what is claimed as new and useful is:

1. In combination with the lighting system of a motor vehicle having a plurality of lighting units, a plurality of filaments in each of said units, a filament of one unit corresponding with a filament in the other unit, a plurality of relay cores corresponding in number to the number of units, a plurality of windings on each of said cores corresponding in number to the number of filaments in each of said units, a source of current, circuits for connecting corresponding filaments in parallel with each filament in series with a corresponding relay coil, switch means for selectively closing any one of said parallel circuits and for simultaneously closing a plurality of said circuits, and a signal circuit including a switch means controlled respectively by the core with which it is associated, and a proving device in said signal circuit.

2. In combination with the lighting system of a motor vehicle having a plurality of lighting units, a bright and a dim filament in each of said units, a plurality of relay cores corresponding in number to the number of units, a plurality of windings on each of said cores corresponding in number to the number of filaments in each of said units, a source of current, circuits for connecting bright filaments in parallel and dim filaments in parallel with each filament in series with a corresponding relay coil, switch means for closing the circuit to all the dim filaments, or all the bright filaments, or to both the dim and bright filaments, and a signal circuit including a switch means controlled respectively by the core with which it is associated, and a proving device in said signal circuit.
